(57) **CLAIM**

The ornamental design for an accordion-folded container, as shown and described.

DESCRIPTION

The claimed design may be used as a lubricant container. FIG. 1 is a front view of an accordion-folded container embodying the ornamental design; FIG. 2 is a back view of the container of FIG. 1; FIG. 3 is a left side view of the container of FIG. 1; FIG. 4 is a right side view of the container of FIG. 1; FIG. 5 is a top plan view of the container of FIG. 1; and, FIG. 6 is a bottom view of the container of FIG. 1.
